(57) **CLAIM**

The ornamental design for an insertion aid for catheter, as shown and described.

DESCRIPTION

FIG. 1 is a perspective view of an insertion aid for catheter showing my new design;

FIG. 2 is a perspective view thereof;

FIG. 3 is front plan view thereof;

FIG. 4 is a left side elevational view thereof; the right side elevational view is a mirror image of the left side elevational view;

FIG. 5 is a rear elevational view thereof;

FIG. 6 is a top plan view thereof; and,

FIG. 7 is a bottom plan view thereof.

CERTIFICATE OF CORRECTION

PATENT NO. : D678,522 S
APPLICATION NO. : 29/394150
DATED : March 19, 2013
INVENTOR(S) : Evelina Gustavsson

Page 1 of 1

It is certified that error appears in the above-identified patent and that said Letters Patent is hereby corrected as shown below:

ON THE TITLE PAGE:

At item (30), change the **Foreign Application Priority Data** to read as follows:

-- Dec. 15, 2010 (EM) ..... 001250054-0001 --.

Signed and Sealed this
Eleventh Day of June, 2013

Teresa Stanek Rea
Acting Director of the United States Patent and Trademark Office
